UNITED STATES PATENT OFFICE.

ROBERT MEYER, OF MÜLHEIM-RUHR, GERMANY.

AUTOMATIC PLATE-VALVE.

1,019,683.

Specification of Letters Patent.

Patented Mar. 5, 1912.

Application filed August 26, 1910. Serial No. 579,144. **REISSUED**

To all whom it may concern:

Be it known that I, ROBERT MEYER, a subject of the German Emperor, and residing at Mülheim-Ruhr, Germany, have invented 5 certain new and useful Improvements in Automatic Plate-Valves, of which the following is a specification.

My invention relates to automatic plate-valves, in which the valve plate consists of a 10 simple strip-shaped leaf spring of constant section which lies extended on the valve seat, is weakened neither by holes nor slots, and becomes bent upwardly by the flowing medium. In the well known valves of this 15 type the strip-shaped plate is firmly clamped at one end while its other end is mounted displaceable longitudinally in order to enable the valve plate to bend upward. This known arrangement has the material disadvantage that the two ends of the 20 plate are subjected to bending stresses and stresses due to axial compression which impair the durability of the plate, particularly at the fixed end, and unavoidably cause the 25 plate to fracture. Further, the ready movability of the valve is imparted in consequence of the ends of the plate bending.

A primary object of my invention is to 30 provide a plate-valve to which the defects described above are not attached, and which is particularly adapted for use in pumps for conveying gases and liquids. To this end, I mount the valve-plate in such manner on the valve seat that it can bend upward the intended height without being subjected at any place to the least lateral flexure or excessive transverse stress and without the departing from the normal bending-line.

40 One illustrative embodiment of my invention is represented by way of example in the accompanying drawing, wherein:—

Figure 1 is a longitudinal section through the closed valve and Fig. 2 a like section 45 through the open valve; Fig. 3 is a cross-section in the line A—B in Fig. 1, while Fig. 4 is a plan view of the plate only.

Referring to the drawing, an elastic, thin, 50 metal strip *c* of constant section rests on the valve seat *a* which is provided with one or more slots *b*. Above the valve seat is arranged in well-known manner a cap or arrester *d* having a recess *e* of arc-shaped section whose crown is on the center line

A—B and exactly determines the form of 55 arc of the plate *c* when it is bent upwardly by the flowing medium. Flat recesses *f* are provided in the cap or arrester, and allow the ends of the plates the very little play required for their movement and assure 60 their correct position relatively to the seat. Inclined faces *h* in the valve-seat *a* below the recesses *f* prevent the strip *c* from being lifted parallel to the face of the seat. The recesses *f* are enlarged, preferably tri- 65 angularly, for the free play of the ends of the strip, as shown at *h*. By means of this arrangement I provide in a new manner that the strip is bent upward by the flowing medium according to a perfectly uniform 70 bending-line in such manner that injurious lateral flexure or excessive transverse stresses due to bending do not occur at any part of the strip. Accordingly, the subject- 75 matter of my invention differs from well-known valves of the type described in that the elastic plate *c* is mounted in such manner that, when the valve moves, it behaves like a loaded, elastic rod resting on two 80 supports.

In special cases I may make the plate broader in the center in the event of greater section of valve being requisite with a given length; also, I may arrange several plates superposed or beside one another for obtaining larger connected systems of valves. Further, by making the face of the seat slightly concave a certain tension can be given in the simplest manner to the strip 85 pressed by the ends of the arrester. 90

The subject-matter of my invention can be employed equally well both as a pressure and as a suction valve. The scope of my invention is not departed from when the material of the valve or plate is made of some 95 other elastic material instead of metal, according to the nature of the medium which is supplied in each instance, or when the subject-matter of my invention is employed for any other purposes than for pumps for 100 conveying gases and liquids.

I claim:—

1. An automatic plate-valve of the type described, comprising in combination a valve-seat having recesses with inclined 105 faces, a thin elastic plate or strip extending into said recesses, and a cap or arrester having a recess of arc-shaped section holding

the plate or strip on the valve seat and exactly determining the upward movement of the same.

2. An automatic plate-valve of the type 5 described, comprising in combination a valve-seat having two recesses with inclined faces, a thin elastic, oblong, metal plate extending into said recesses, and a cap having a curved recess and two recesses at the 10 ends of the plate for holding the plate on

the valve-seat and exactly determining the upward movement of the same, substantially as shown.

In testimony whereof, I have signed my name to this specification in the presence of 15 two witnesses.

ROBERT MEYER. [L.S.]
